SNAP SWITCH WITH OSCILLATING KNOB

Victor R. Despard, Syracuse, N. Y., assignor to Pass & Seymour, Inc., Syracuse, N. Y., a corporation of New York

Application September 5, 1951, Serial No. 245,107

20 Claims. (Cl. 200—6)

This invention relates to electric switches, and more particularly to wall switches of the so-called alternating current type adapted to be actuated by an oscillatable knob.

It is a general object of the present invention to provide a novel and improved switch of the A. C. type having a knob actuator intended for relatively small angular movement in either of two directions for actuating the circuit opening and closing mechanism.

More particularly it is an object of the invention to provide in a switch of the type described combined resilient contact carrier means and buffering or motion limiting means for the actuating knob.

An important object of the invention comprises the arrangement of a switch housing with projecting actuating knob and guiding spindle journaled therein, together with a stationary contact and a cooperating contact intermediate the ends of a cantilevered spring whose free end is engageable by a projection on the lower surface of the knob for actuation thereby.

Another important object of the invention consists in the arrangement of an oscillatable knob having an axial spindle fitted with an over-center spring for urging the rotation of the knob in either of two directions when it is manually moved beyond the center, together with a knob motion buffer and contact carrying system including a spring cantilevered from the housing and having a free end positioned for cooperation with a projection on said knob.

A still further object of the invention comprises the arrangement in a three-way A. C. switch of a pair of parallel spaced cantilevered springs mounting intermediate their ends contacts for engagement with straddling stationary contacts and incorporating an operating mechanism of the oscillatable knob type having an over-center spring wherein the free ends of the contact carrying springs are received in slots in the knob for movement by the walls thereof and for limiting the motion of the knob under the action of its spring.

One of the important features of the present invention resides in the construction and arrangement of the switch parts to produce contacting operations which vary from quiet to silent by the elimination of snap action and leaving control of the contact carrying spring with the operator until contact is made.

Other and further objects of the invention will be more apparent to those skilled in the art upon a consideration of the accompanying drawing and following specification, wherein there is depicted the single exemplary embodiment of the invention, with the understanding that such modifications may be made therein as come within the scope of the appended claims without departing from the spirit of the invention.

In said drawing:

Fig. 1 is a longitudinal central section through a switch constructed in accordance with the present invention;

Fig. 2 is a top plan view thereof with the cover and knob removed and the operating spindle in section;

Fig. 3 is a transverse central section taken on line 3—3 of Fig. 1;

Fig. 4 is a bottom plan view of the cover showing the under face of the knob disk and its operating projections, the upper free ends of the contact carrying springs being illustrated in dot and dash lines to show their cooperation with the operating projections; and

Fig. 5 is a view similar to Fig. 4 but illustrating a modi-

fication in which limit lugs on the cover determine the maximum movement of the contact springs.

The switch of the present invention is primarily intended for but not necessarily limited to use in wall and switch boxes for general interior wiring and may be mounted in multiple with other wiring devices in a single gang box in a known manner, by being supported from a strap or bridge plate. For this purpose it is shown as fitted with a suitably shaped and sized housing 10 of molded insulating material having a closed bottom wall 11, closed side walls 12 and similar longitudinally slotted end walls 13. The top is open, providing a large interior chamber intended to be closed by a cover plate 14 of insulating material and having a protuberant neck 15 for mounting in the strap and acting as a guide for the operating knob assembly 16, which includes the external longitudinally fluted portion 18 for manual manipulation, the interior bearing portion 19 and the enlarged bottom disk or radial flange 20, equipped on the under surface at the periphery with the spaced operating lugs 21, 22 and 23.

The operating knob assembly is molded about or otherwise attached to the upper end of a sheet metal spindle 25 axially disposed and extending from the lower or disk end thereof and having a narrowed lower end 26 the edge 26' of which is at the axis line. This end 26 is received in opening 27 in the bottom wall of the housing. The opening is V-shaped as shown to provide a fulcrum for edge 26'. The under face of the cover 14 of the housing is provided with a recess 30 for the disk 20 which forms the upper thrust bearing for the knob and spindle assembly.

Integral with the spindle and projecting radially therefrom is the arm 32 which is given a 90° twist and notched at the outer end as at 33 to fit over the wire of an over-center spring 34, generally of U-shape having the shorter leg provided with a crimped portion 35, the bottom of which engages in notch 33 to position the spring in the vertical direction in the housing. The long arm of the spring rides in a narrow V-channel 36 in the adjacent side wall of the housing. Sufficient compression is effected in the assembly operation so the spring acts as an over-center device and throws the spindle to the limit of its oscillatory movement in either direction, if it is first manually passed over-center by manipulation of the knob. Throw limit for the knob is effected by engagement of a projection 37 on the portion 19 with end walls of a channel 38 in the neck of the cover (Fig. 3).

The contact structure of the switch is extremely simple and comprises, for a three-way switch, two sets of contacts each including a stationary contact 40 and a movable contact 41. For a single pole switch one set may be omitted with the associated carrying parts therefor. Preferably, however, the second set of parts may be dummies for a purpose which will appear later. The stationary contacts are supported in the desired position straddling the movable contacts by arms 42 of the configuration best shown in Fig. 1. The contacts are riveted to the right angled ends 43 thereof and the opposite ends are bent out at right angles from integral terminal plates 44 of a width sufficient to have their ends received in the channels 45 in the vertical corners of the housing. These terminal plates each received a terminal screw 46, the head of which is accommodated in slot 47 in the end wall of the housing, as shown. These slots have flaring side walls for convenience in wiring.

Movable contacts 41 are each riveted intermediate the ends of one arm 50 of a U-shaped spring 51, the central portion of which is riveted at 52 to connector strap 53 extending longitudinally along the bottom wall of the housing and having an upturned integral terminal plate 54 thereon, which is also received, at one side in the channels 45 in the corners of the housing. The two terminal plates 44 and 54 on the left side of Fig. 1 are spaced apart vertically by a horizontally arranged barrier plate of insulating material 56 notched to receive the walls of the slot 47 for positioning. The terminal plate of the opposite stationary contact is held in its upper position by resting on a sheet of insulating material 57 in the channels 45 beneath it. The upper edges of the terminal plates 44 are engaged by the housing cover 14 which is in turn held in position by a metal collar 60

secured to the housing in a known manner. This maintains the assembly and holds all the parts in rigid position. It will be noted that the insulation plate 57 beneath the terminal plate 45 on the right side of Fig. 1 bears on the far end of the spring carrying strap 53 and holds it rigid.

Fig. 2 illustrates the offset arrangement of the conductor strap 53 to position the U-shaped spring between the stationary contacts which are along one side of the housing.

Each movable contact is positioned at a nodal point in the length of its cantilevered spring arm 50 to produce a minimum of vibration or chattering during the closing operation. The spring arms are initially bent to substantially the position shown in the one to the right in Fig. 1 to insure adequate contact opening under the urge of the spring. Closing is effected by engagement of the central boss or lug 22 on the knob disk with either of the springs, dependent upon the positioning of the knob under the action of its over-center spring. The lug 22 not only flexes the spring sufficiently to engage the movable contact with its stationary counterpart but provides supplemental flexing as shown at 62 in Fig. 1 to insure adequate contact pressure. This is maintained under the action of the over-center spring 34.

The single central lug 22 serves to alternately engage the movable contact springs, closing one and releasing the other to open its contact by its own resilience. However, in the event that there should be contact sticking from arcing or heating, kick-off knobs of lugs 21 and 23 are provided spaced on opposite sides of the operating lug but sufficiently spaced from them to avoid striking the release side of the spring until there has been some considerable movement of the knob to provide impact after the knob has moved over center. They, however, do each engage the back face of the corresponding spring, as shown in Fig. 4, when the knob has reached its limit of stroke, even though the spring has carried the contacts apart to insure against any accidental closing from shock or vibration.

Mention has previously been made of the stroke limiting means 37 for the knob, but this is only a safety device to prevent accidental excessive movement manually, for the knob is stopped prior to effective action of this by the engagement of the corresponding set of contacts and the flexing of the spring 50 at 62. This provides a cushion or resilient stop for the knob and quiets the switch to the extent that the only sound produced is that resulting from the engagement of the contacts. Since the stroke is short and the speed not high, the sound is almost imperceptible and can be reduced or stopped entirely by intentional slow movement of the knob to the end of its stroke.

Thus it is possible for the operator to retain control of knob movement until after the contacts engage. In fact in normal operation the forefinger and thumb remain on the knob for its full stroke. Since the full stroke is only about 20° this is simple. The springs therefore perform the dual function of carrying the contacts and limiting and cushioning the stroke of the operating knob. The switch is therefore much more quiet than the usual lever type where the contact elements, after initial movement, are no longer under control of the lever.

The switch of this invention is small in size, cheap to construct, effective in operation, has increased current carrying capacity and has a small number of simple parts. It can be adapted for many uses.

In order to further quiet the switch, the cooperating stop lug 37 on the knob and the end walls of the channel 38 in which it travels may be eliminated entirely and the construction shown in Fig. 5 substituted. Here the cover 14 for the housing has depending lugs 65 so positioned as to limit the throw of the contact carrying springs to the amount shown in Fig. 1 at the left. These lugs are each engaged by the corresponding tip of the adjacent spring under the urge of operating lug 22 and hence stop motion of the knob assembly in a resilient manner to reduce noise. This arrangement necessitates the use of a dummy spring and contact in single pole switches. However the cost of the U-shaped spring is not substantially greater than an L-shaped one. No contact is needed on the dummy spring and only a projection on the carrier for the stationary contact. Its supporting plate will have no terminal screw.

I claim:

1. An A. C. switch having in combination, a spring leaf fixed at one end, a contact button intermediate the ends of said leaf, a fixed contact button, means rigidly positioning said fixed contact button to cooperate with the first button when the latter is moved by flexing the leaf, a knob for manual manipulation, means guiding said knob for oscillation on an axis roughly parallel to that of the said leaf, abutments beneath said knob spaced apart a distance equivalent to several times the thickness of and straddling the free end of said spring leaf to individually flex the same and resilient over-center means cooperating with said knob to hold it at either limit of its movement.
2. The A. C. switch of claim 1 in which the fixed and stationary contacts are provided in duplicate, the stationary contacts facing each other with the movable contacts between whereby the stationary contacts are alternatively engaged by their corresponding movable contact, said knob having a third abutment with one of the first pair straddling the second contact spring.
3. In a switch of the type described, in combination; a housing having a chamber therein open at the top; a cover for said open top; an opening in said cover, a knob extending through said opening and having a flange engaging the inner face of the cover, a leaf spring having one end fixed adjacent the bottom of said chamber and the free end just clearing the under surface of said flange near the periphery thereof, a contact intermediate the ends of said leaf, a stationary contact carried by said housing for cooperation with the movable contact when the spring is flexed, and means depending from said flange to engage the free end of the spring and flex the same to press said contacts together when the knob is partially rotated in the proper direction.
4. The switch as defined in claim 3 including an over-center spring cooperating with said knob to hold it in either of two selected positions.
5. The switch as defined in claim 4 in which said knob flange is fitted with a second depending means to effect positive separation of said contacts.
6. In a switch of the type described; in combination; a hollow, open-topped housing; a cover for said housing having a central opening therethrough; a knob extending through and journaled in said opening and having an axially disposed spindle journaled in the bottom of said housing, a flange disc on the knob engaging the under surface of the cover, a laterally extending arm on said spindle, a spring compressed between said arm and a wall of the housing for over-center movement as the knob is oscillated, a leaf spring having one end fixed adjacent said bottom and extending toward and with its free end just clearing the under surface of said disc near the periphery thereof, a stationary contact supported from the housing, a contact intermediate the ends of said leaf spring and supported thereby clear of but for cooperation with the stationary contact and an abutment depending from said disc to engage and flex the free end of the spring on movement of the knob and thereby press and hold the contacts together under the action of the over-center spring.
7. The switch as defined in claim 6 in which stop means is provided for said knob to limit its movement in contact opening direction.
8. The switch as defined in claim 7 in which the stop means comprises a duplicate set of fixed and spring mounted contacts arranged to be closed by the said abutment when the latter is moved to open the first contact set.
9. The switch as defined in claim 8 in which said knob disc is provided with additional abutments one spaced circumferentially on each side of the first to positively engage and move one spring in contact opening direction as the other is moved in contact closing direction.
10. The switch as defined in claim 8 in which the two contact carrying springs are the arms of a U-shaped unit, and a combined terminal and mounting plate secured to the base of said unit and positioned in the bottom of said housing.
11. In a switch of the type described, in combination, a base; a switch operator including a knob mounted on said base for manual oscillation, an over-center spring positioned between said operator and base to move the operator in each direction to a limit, a pair of leaf springs cantilevered from said base adjacent the axis of knob oscillation and each having a free end, each positioned to

be engaged by and resiliently limit movement of the operator in one direction, a contact carried by one of said leaf springs intermediate the ends thereof, and a stationary contact supported from said base and engageable by said spring-carried contact under the urge of said over-center spring.

12. In a switch of the type described, in combination, a housing, a switch operator in the housing mounted for partial rotation about an axis normal to the front of the housing, a knob directly and rigidly connected to the operator and extending from the front of the housing, an over-center spring acting directly between the housing and operator to move the latter to a limit in either direction when moved past mid-position by said knob, a stationary contact rigidly mounted in said housing, a cantilever spring extending from the rear wall of said housing and having a free end positioned for engagement by said operator for movement thereby, and a contact intermediate the ends of the cantilever spring for electrical engagement with the stationary contact, said operator when moved in one direction by its spring advancing said contacts toward each other and vice versa, engagement of said contacts serving to limit operator movement in one direction.

13. The switch as defined in claim 12 in which the cantilever spring biases the contacts apart and means on said operator to engage the cantilever spring to positively separate the contacts when the operator is moved for that purpose.

14. The switch as defined in claim 12 in which said operator and said housing are fitted with cooperating stop means to limit operator movement in the direction opposite from the contact engaging one.

15. The switch as defined in claim 12 wherein duplicate cantilever springs, movable and stationary contacts are provided and the switch operator is provided with off-center projections for each cantilever spring, each adapted to engage an opposite side of said free end of the corresponding cantilever spring to move its contact in opening or closing directions, said projections being spaced apart so that in either rest position of the operator each spring is spaced from one of its operating projections such a distance that it is not engaged thereby until the switch operator is moved at least to mid-position.

16. In a switch of the type described, in combination, a hollow housing substantially rectangular in cross-section, a terminal plate at one end wall having an integral strap lying along the bottom of said housing and offset to one side thereof, a U-shaped spring having its bottom secured to said strap with the free cantilever arms of the U extending alongside one side wall of the housing and substantially parallel to the end walls, a switch operator oscillatable on an axis through the centers of the housing top and bottom walls and including a finger knob projecting above the top wall, a contact button on an intermediate portion of one of said spring arms and facing the adjacent outer wall, a second terminal plate at an end wall of the housing, a rigid arm on said last mentioned plate, a contact button on said arm in confronting but separated relation to the spring mounted button, means on said operator to engage the free end of said one arm and flex it to bring the contacts together, and over-center spring means arranged to hold the operator in either one of contact engaging or releasing positions.

17. In a slow-break switch, in combination, a housing, terminal plates recessed in and carried by the end walls of said housing, a contact rigidly supported by one of said plates, a second contact spaced from the first, a cantilever spring blade supported at one end by the other plate and carrying the second contact intermediate its ends, a turn knob journaled in the housing on an axis substantially parallel to the said blade and overlying the free end of the blade, an eccentric projection depending from the undersurface of said knob positioned to flex the blade and engage the contacts and over-center means within the housing connected to urge the knob toward or from contact closing position.

18. A slow-break A. C. switch of the type including a stationary contact, a confronting movable contact, a cantilever spring fixed at one end, having a free end and supporting said movable contact at such a position intermediate the spring length as to provide low vibration amplitude when the free end of the spring is engaged to move the contacts together, a switch operator including a finger knob and a shaft coaxial thereto, means mounting said assembly for oscillation about its longitudinal axis positioned parallel to the longitudinal axis of the spring, over-center means urging said operator toward an end of its oscillation stroke and means on said operator to alternatively engage one or the other side of said free end of said spring to flex the same toward or away from contact engagement.

19. A slow-break A. C. switch of the type including a stationary contact, a confronting movable contact, a cantilever spring fixed at one end and supporting said movable contact for movement therewith, a switch operator including a finger twist knob and a shaft coaxial thereto and positioned with its longitudinal axis substantially parallel to said spring, means mounting said assembly for oscillation about its said axis, over-center means urging said operator alternately toward one end of its oscillation stroke and means eccentrically disposed on the undersurface of said knob to alternatively engage one or the other side of said spring to flex the same toward or away from contact engagement.

20. The switch structure of claim 19 in which the switch operator stroke is normally limited in one direction by the engagement of the contacts.
